UNITED STATES PATENT OFFICE.

GARDNER V. RAMSEY, OF BROOKSVILLE, FLORIDA.

HARNESS-BUCKLE.

No. 920,996.

Specification of Letters Patent.

Patented May 11, 1909.

Application filed June 30, 1908. Serial No. 441,117.

To all whom it may concern:

Be it known that I, GARDNER V. RAMSEY, a citizen of the United States, residing at Brooksville, in the county of Hernando, State of Florida, have invented certain new and useful Improvements in Harness-Buckles; and I do hereby declare the following to be a full, clear, and exact description of the invention, such as will enable others skilled in the art to which it appertains to make and use the same.

This invention relates to buckle devices for attachment to the harness in position to be engaged by the reins to prevent them from lateral movement where they pass over the back of the horse, and has for one of its objects to provide a simply constructed device which may be attached to the hip straps and against which the reins engage and are thus prevented from slipping down from the hips of the horse and becoming entangled in projecting portions of the harness.

With these and other objects in view the invention consists in a buckle frame having spaced transverse bars through which the hip straps are adapted to be woven and with a tongue swinging upon one of the bars and engaging the strap, and an outwardly curving loop at one end of the frame against which the reins are adapted to engage, and be thus prevented from slipping down over the hips of the horse.

The invention further consists in certain novel features of construction as hereafter shown and described, and then specifically pointed out in the claim, and in the drawings illustrating the preferred embodiment of the invention, Figure 1 is a side elevation of the improved buckle applied. Fig. 2 is a plan view of the same. Fig. 3 is a perspective view of the improved buckle detached.

Much annoyance is encountered in driving horses by the tendency of the reins when loosened to slip down over the hips of the horse and become entangled in projecting portions of the harness, especially with the loose ends of the billets of the breeching straps or connections, and likewise with the tail of the horse, and the principal object of the present invention is to provide a simply constructed attachment for the hip straps relatively near the juncture of the back straps and hip straps and adapted to

be engaged by the reins and thus prevented from slipping down over the hips, the improved device comprising an oblong frame formed of side members 10-11 and transverse members 12-13 with an intermediate transverse member 14, the member 14 provided with a swinging tongue 15 of the usual form, the hip strap represented at 16 adapted to be woven through the frame and engaged by the tongue 15 which is adapted to enter one of a series of holes 17 in the hip strap so that the improved device may be adjusted to any required extent within the range of the holes upon the hip straps.

Extending from one end of the frame is a loop 18 curving outwardly from the side members of the frame and thus forming an effectual stop against which the reins indicated at 19 will be engaged and thus effectually prevented from slipping down over the hips of the horse. The curved portion 18 will be of sufficient length and project a sufficient distance from the hip straps to prevent the reins under the normal conditions from slipping past the loop.

The improved device is simple in construction, can be inexpensively manufactured, and of the same material as other metal portions of the harness, and may be plated, tinned, japanned or otherwise treated in the same manner as ordinary harness buckles and other metal attachments, and can be readily applied to the hip straps without change therein except to provide the spaced hole 17 for the tongue 15.

What is claimed, is:—
The combination with the hip straps of a harness, of an oblong buckle frame through which said hip strap passes formed with an intermediate cross bar, a tongue swinging upon said intermediate cross bar and passing through said strap and bearing by its free end upon one of the end bars of the frame, and a U-shaped loop extending from the end bar with which the tongue engages and arranged at an angle to the longitudinal plane of the frame, whereby the loop is spaced away from the hip strap.

In testimony whereof, I affix my signature, in presence of two witnesses.

GARDNER V. RAMSEY.
